CUTTING TOOL

Emmerich Schmitt, 3665 Shasta Drive, Brookfield, Wis.

Filed June 11, 1965, Ser. No. 85,674

Term of patent 14 years

(Cl. D54—4)

FIG. 1 is a front view of the cutting tool.

FIG. 2 is a side view in elevation.

FIG. 3 is a rear view of the same.

FIG. 4 is a plan view taken in the direction of line 4—4 of FIG. 1.

FIG. 5 is a cross-sectional view taken along line 5—5 of FIG. 1.

FIG. 6 is a cross-sectional view taken on line 6—6 of FIG. 1.

I claim:

The ornamental design for a cutting tool, as shown.
